United States Patent Office.

WILLIAM P. ALCORN, OF NEW WILMINGTON, PENNSYLVANIA.

Letters Patent No. 92,557, dated July 13, 1869.

IMPROVEMENT IN WAGON-BRAKES.

The Schedule referred to in these Letters Patent and making part of the same.

To all whom it may concern:

Be it known that I, WILLIAM P. ALCORN, of New Wilmington, in the county of Lawrence, and State of Pennsylvania, have invented certain new and useful Improvements in Wagon-Brakes; and I do hereby declare that the following is a full, clear, and exact description thereof, reference being had to the accompanying drawings, and to the letters of reference marked thereon, which form a part of this specification, and in which—

Figure 1 represents a side view, and

Figure 2, a bottom or inverted view of my wagon-brake.

Similar letters of reference indicate like parts in both figures.

My invention relates to improvements in wagon-brakes; and to this end

It consists in the employment of levers, brakes, pitmen, and cog-segments, arranged to operate substantially in the manner and for the purpose hereinafter described.

To enable others skilled in the art to which my invention appertains, to make and use the same, I will now describe its construction and operation.

In the accompanying drawings—

A represents the wagon;

B the wheels; and

C the axle-tree, to which the tongue D is attached in the usual manner.

On the tongue D is secured the cross-bar E, to each end of which are attached the stops a a, pressing against the wheels B B.

a represents a rod, secured to the tongue, and provided at one end with the projection b, by which it is attached to the cross-bar E by the rod b'.

The other end is provided with the lever c, the lower

end being connected with the cross-bar E by means of the rod b''.

The upper end of lever c is attached to one end of the rod c', the other end of the rod c' being attached to the tooth-bar d, working in the metal plate d', secured to the outer side of the wagon.

e is a tooth-projection, formed on the upper end of the plate d'.

F represents a lever, pivoted at its lower end to the wagon, and attached near the point of pivoting to the cog-segment f, working in the tooth-bar d, as seen in the drawings.

The lever F is formed with a metal projection, f', arranged so as to work in the tooth-projection e. By this arrangement of rods and lever, a perfect brake is formed.

Having thus described my invention,

What I claim as new, and desire to secure by Letters Patent, is—

1. The lever F, in combination with the tooth-segment f and tooth-bar d, substantially in the manner and for the purpose described.

2. The plate d', provided with tooth-projection e, in combination with lever F, cog-segment f, and tooth-bar d', all arranged and operating substantially in the manner and for the purpose set forth.

3. A wagon-brake, consisting of the lever F, cog-segment f, tooth-bar d', rods b b'', lever c, cross-bars E, provided with stops a a, and cross-rod a'; all combined, arranged, and operating substantially in the manner and for the purpose set forth.

In testimony that I claim the foregoing as my own, I affix my signature, in presence of two witnesses.

Witnesses:
